UNITED STATES PATENT OFFICE.

FRANK WITHERSPOON, OF PARIS, TEXAS.

WINDMILL.

SPECIFICATION forming part of Letters Patent No. 279,066, dated June 5, 1883.

Application filed August 5, 1882. (No model.)

To all whom it may concern:

Be it known that I, FRANK WITHERSPOON, a citizen of the United States, a resident of Paris, in the county of Lamar and State of Texas, have 5 invented a new and valuable Improvement in Windmills; and I do hereby declare that the following is a full, clear, and exact description of the construction and operation of the same, reference being had to the annexed drawings, 10 making a part of this specification, and to the letters and figures of reference marked thereon.

Figure 1 of the drawings is a top view of my windmill. Fig. 2 is a side view, and Figs. 3 and 4 are detail views.

15 This invention has relation to wind-wheels turning around a vertical axis; and it consists in the construction and novel arrangement of the radial arms of the wheel-frame and the vertical pivot-posts thereon, the sails or fans 20 pivoted to said posts, the pivoted detents, and the pivoted governing-levers to which said detents are connected, said levers carrying adjustable weights, all as hereinafter set forth.

In the accompanying drawings, the letter A 25 designates the main pivot-post of the wind-wheel, having a pivot-bearing at its upper end, on which is seated the center plate or cap-plate B, having marginal sockets or bearings C, to receive the inner ends of the radial arms D of 30 the wheel, which extend in the horizontal direction.

To the outer ends of the arms D are secured the vertical pivot-posts E, to each of which a sail or fan, F, is pivoted on bearings g of the post, 35 so that the sail or fan can swing entirely around said post. The sails or fans may be made of canvas, stretched on suitable frames, or they may be of metal or wood, or both. Usually they are of rectangular form, and, whatever be 40 their shape, the lower edge h should be arranged to pass near the upper surface of the radial arm D as the wheel rotates.

To one side of each arm D is pivoted a detent, K, the upper end of which projects sufficiently 45 above the upper surface of said arm to engage the lower edge of the sail or fan near its free end, as shown in the drawings. The detent is provided with a series of perforations or bearings, l, for the pivot-pin m, so that it is adjusta-

ble, and can be arranged to project more or less 50 above the surface of the radial arm, according to the rate of speed at which a disengagement is required to be effected.

Connected by a rod or strip, N, to the lower end of each detent is a depending lever, P, which 55 is pivoted at its upper end to the outer end of the arm D, and attached to the lower end of this lever is the adjustable weight W. The position of this weight determines the height to 60 which the lever will rise at a given rate of speed of the wheel, and the lever is designed to act as a governor to operate the detent K in a high wind, turning said detent downward so that it will not engage the sail or fan, and thereby allowing said sail or fan to swing freely in the 65 wind, so that the revolutions of the wheel are checked.

It will be observed that the detent of each arm D holds the sail pivoted to the post thereof during a little more than a half-revolution, and 70 then the action of the wind disengages the sail from the detent and causes it to swing freely in returning toward the wind. The power of the wind is thus rendered effective on the same side of the wheel constantly, and the wheel will 75 move about its vertical axis with great rapidity. At the same time the governing-levers will swing outward and upward. Should the wind become high, tending to break or injure the operating parts of the wheel, the governing-levers will be caused to rise still higher, and will 80 disengage the detents from the sails, allowing them to swing freely in the direction of the wind on all the arms of the wheel.

Each sail or fan may be provided with an 85 arm, on which an adjustable governing-weight may be arranged.

The detents may be arranged one at the top and another at the bottom of each fan, if of large size; or a central arrangement may be adopted. 90

A governor has been connected to the main shaft or post of a wind-wheel in such a manner as to raise and lower projections on a sleeve encircling the shaft and cause them to become engaged with and disengaged from the pivotal 95 blades of the wind-wheel to regulate the speed; and this construction is not broadly claimed herein.

Having described this invention, what I claim, and desire to secure by Letters Patent, is—

A wind-wheel consisting of a central bearing having horizontal arms D, pivot-posts E thereon, sails or fans F, pivoted to said posts, pivoted detents K, pivoted governing-levers P, connected to said detents, and the adjustable weights W on said levers, substantially as specified.

In testimony that I claim the above I have to hereunto subscribed my name in the presence of two witnesses.

FRANK WITHERSPOON.
